Primary Examiner — Kevin K Rudzinski

(74) Attorney, Agent, or Firm — Honigman LLP

(57) **CLAIM**

The ornamental design for an air flow deflector, as shown and described.

DESCRIPTION

FIG. 1 is a front/top/right side view of the airflow detector of the present invention;

FIG. 2 is a right side elevational view of the embodiment of FIG. 1, the left side elevational view being a mirror image thereof;

FIG. 3 is a top view of the embodiment of FIG. 1; and, FIG. 4 is a front elevational view of the embodiment of FIG. 1.

The broken lines shown in the drawings illustrate portions of the air flow deflector that form no part of the claimed design.
